1

This invention relates to automatic frequency control and more particularly to automatic frequency control for generators operating at frequencies above 500 megacycles.

One method presently employed to control the frequency of a generator generating waves having a frequency above 500 megacycles is to compare the operating frequency of the generator with the resonant frequency of a low loss or high "Q" circuit. In accordance with this method some of the energy from the generator is impressed on the high "Q" circuit. Part of the oscillatory energy is then taken from the circuit, detected and the amplitude of the detected output is observed. Variations in the amplitude of the detected output represent changes in frequency away from the frequency of the resonant circuit. This arrangement, however, leaves much to be desired since it indicates only the amount of frequency change and not the direction of that change.

One way of determining the extent, as well as direction, of the frequency change would be by the use of two high "Q" circuits, one tuned above and one tuned only below the desired operating frequency of the generator. Since such low loss or high "Q" circuits must be very stable, they are quite expensive in view of the precision required in their construction.

In order to avoid the use of two such low loss circuits, and thereby reduce the cost of the apparatus, it has been proposed to continuously and cyclically vary the tuning of a single low loss or high "Q" circuit about the desired operating frequency. This can be done by means of a properly shaped rotating condenser plate coupled to the low loss circuit.

Heretofore, a detector coupled to the output of this resonant low loss circuit, whose tuning is varied as indicated, fed its resulting output voltage to a commutator arranged to be integral with the cyclically varied tuning condenser to thereby generate or produce a voltage whose polarity is of one sign when the operating frequency is above the tuning of the low loss circuit and of the opposite sign when below the assigned or desired frequency. One object of my invention is to provide a system which does not make use of a commutator and thereby avoids the difficulties concomitant to its use. In carrying out this object, I make use of a balanced detector system, as will be described more fully hereinafter, in place of the commutator.

Use of my balanced detector arrangement requires another voltage synchronous with the volt-

2

age generated by the modulating or continuously varied tuning condenser. Heretofore, with the commutator arrangement, a synchronous voltage for use in detecting frequency departures has been generated by means of an alternator mounted on the same shaft as the modulating or tuning condenser. In accordance with my present invention, this alternator is eliminated and the synchronous voltage used in my detector system is derived in a much more satisfactory and practical manner.

Other objects, advantages and features of my present invention will be apparent as the more detailed description thereof proceeds. The latter will be given with the aid of the accompanying drawings wherein:

Figure 1 illustrates one modification of my present invention;

Figures 1a, 1b, 1c and 1d are voltage-time graphs used in describing the operation of Figure 1;

Figure 2 is a variation of Figure 1;

Figure 3 is a modified form of Figure 1 and is characterized by the fact that a voltage is changed in order to correct the frequency of oscillations generated by a generator rather than, as illustrated in Figure 1, change the tuning of a generator in order to correct the frequency of oscillations generated thereby; and

Figure 4 is still another modification or variation of Figure 1 in which a reversible motor for frequency control is operated directly from electronic tubes.

Referring to Figure 1, I have illustrated at 35 1 a low loss high "Q" resonant circuit accurately tuned to a desired operating frequency. Low loss circuit 1 consists of a cylindrical outer conductor 1A and an inner concentric conductor 1B. The resonant frequency of the resonant element

40 1 is varied above and below the assigned or desired operating frequency by means of rotating disc 2 mounted on the shaft of and driven by synchronous motor 3. Disc 2 is cut away or notched, as shown at 2E, 2F, 2G and 2H, so as 45 to have four condenser poles 2A, 2B, 2C and 2D. As illustrated, these condenser poles rotate through a slot in the outer conductor 1A of the concentric transmission line 1 and cause the resonant frequency of the low loss device 1 to 50 vary equally above and below the desired operating frequency.

Radio frequency oscillations are fed from the high frequency generator HFG to the concentric transmission line 5A—5 to a suitable circuit such 55 as an antenna (not shown). By means of the

transmission line section 6 having an internal conductor 6A and coupling loops 6B and 6C, high frequency oscillations from the generator are also fed through the action of loop 6B, conductor 6A and loop 6C to the resonant low loss circuit 1.

By means of loop 4A and the inner conductor 4B of transmission line section 4C, wave energy is picked up from the low loss resonant circuit 1 and fed to high frequency crystal detector 4 provided with a suitable by-pass condenser 40.

The rectified output of crystal detector 4 is fed through line 4F and transformer T to the control grid of the amplifier-limiter tube 9. The output of limiter 9 is impressed through transformer T₃ in push-pull to the control grids of vacuum tubes VT₁ and VT₂ forming a balanced detector 10.

The source of constant relatively low frequency waves derived from a source LFS, which drives the synchronous motor 3, also supplies transformer T₃ feeding the full wave rectifier 7. Unfiltered rectified voltage from rectifier 7 is fed through condenser C₁ and conductor C₂ to the plates of vacuum tubes VT₁ and VT₂.

The cathodes of detector tubes VT₁ and VT₂ are connected to and actuate polarized relay 11, in turn actuating relays 12, in turn controlling a reversible motor RM used to control the frequency of the high frequency generator HFG. As illustrated, this is accomplished by increasing or decreasing the capacity of the frequency controlling condenser FCC which may form part of the tank circuit of the vacuum tube generator HFG.

The synchronous motor 3 may be a 4-pole motor with a speed of 1800 R. P. M. The rotating condenser pole may be a 4-pole condenser. In operation any one pole of the rotor of the synchronous motor may line up with any of the four poles of the stator. The synchronous motor 3 may take any one of four positions. For this reason the condenser 2 must have the same number of poles as the motor 3 so that the phase of the output voltage from crystal detector 4 will be independent of the position of the synchronous motor 3.

The voltage fed to the plates of balanced detector 10 is rectified full wave, 60 cycles and is represented in Figures 1a, 1b and 1c by E_p. Figure 1d represents a resonance curve of the high "Q" circuit 1. Thus, if the generator frequency is at F₀ the rotating condenser will vary the frequency of 1 between the limits of F₁ and F₂ and the resulting output voltage in crystal 4 will be as represented in Figure 1a by E_{g1} and E_{g2}. E_{g1} is the voltage impressed on the control grid of tube VT₁ and E_{g2} is the voltage impressed on the control grid of VT₂. An examination of Figure 1a will show that the average current drawn by VT₁ will be equal to the average current drawn by VT₂ and the polarized relay 11 will not be operated.

However, if the frequency of the generator shifts to E₁ the modulating condenser 2 will vary the frequency of the circuit 1 between the limits of F₃ and F₀. The output voltage on crystal 4 will be half the frequency that it was for the condition when the generator frequency was F₀. The resulting voltages impressed on the control grids of VT₁ and VT₂ are represented in Figure 1b by E_{g1} and E_{g2}. Examination of this curve shows that VT₁ will draw more current than VT₂ because the grid is plus during the time that the plate voltage is also plus whereas the

grid of VT₂ is negative when the plate voltage is plus. This will operate the polarized relay 11, which will operate relay 12 and start the control motor RM in the proper direction to correct the generator frequency.

If the generator frequency shifts to F₂ the conditions will be as illustrated in Figure 1c. Now the control grid of VT₂ is plus when the plate voltage is plus, while the control grid of VT₁ is negative and, therefore, VT₂ will draw more current than VT₁ and the polarized relay 11 will be operated in the opposite direction, causing the control motor RM to operate in the proper direction to correct the frequency.

In the above the phase of the voltage E_p may be adjusted with respect to the phase of voltages E_{g1} and E_{g2} by locating condenser 2 in the proper position on the synchronous motor shaft. Also, amplifier 9 is operated so that it is limiting. This results in the amplitude of the voltages E_{g1} and E_{g2} to balanced detector 10 being independent of the amplitude of radio frequency voltage coupled into high "Q" circuit 1 and, therefore, substantially responsive only to changes in frequency.

The function of condensers 13 in Figure 1 is to smooth out the pulsating currents which flow through the tubes VT₁ and VT₂ and maintain a more nearly constant current through the D.-C. polarized relay 11. That is, the high peak currents through the tubes VT₁ and VT₂ charge up the condensers 13 which discharge through the relay 11 and the resistor 13A. The average current through this resistor produces a bias for the tubes VT₁ and VT₂.

The above description relates to a 4-pole synchronous motor, but also it would be possible to use a 2-pole synchronous motor. In that case the rotating condenser would have to have two poles P₁ and P₂, as illustrated in Figure 2. Also, if the output from crystal detector 4 were large enough it may be possible to omit amplifier 9 and impress the crystal output voltage directly on the balanced detector 10, as shown in Figure 2.

The output at the balanced detector may be made to control a voltage which will correct the frequency drift of the generator. This may be done for such generators as the "Klystron" oscillator or other oscillators whose frequency is a function of the supply voltage. Specifically, the frequency increases with an increase in plate voltage (increase in electron velocity in beam) in a "Klystron" or similar type of oscillator, and decreases with a decrease in voltage.

Figure 3 shows a circuit for controlling the frequency in this way. The operation and arrangement of the balanced detector 10 are as given in connection with Figure 1. However, it is to be noted that the cathode output circuits of the detector tubes VT₁, VT₂ of Figure 3 are connected in series with one cathode, namely, cathode 10C of vacuum tube VT₂, grounded.

As a consequence, in Figure 3 a D. C. output voltage at terminal 17 will appear which will be negative or positive with respect to ground depending upon whether the frequency of the high frequency generator HFG (see Figure 1) is above or below its assigned value.

The voltage at terminal 17 of Figure 3 is impressed through a suitable resistance and condenser filter on the control grid of vacuum tube amplifier T₄. Vacuum tubes T₄, T₅ and T₆ serve to regulate the power supply at terminals a, b connected to the oscillation generator.

The voltage impressed on the control grid g₄

of electron discharge device T_4 from potentiometer 16 by way of tap 316 is amplified by tubes T_4 and T_5 and impressed on the grid G_6 of vacuum tube T_6 in such a way as to maintain the voltage across the output terminals a and b constant.

The function of the glow tubes GT_1 and GT_2 of Figure 3 is to maintain the cathodes C_4 and C_5 of vacuum tubes T_4 and T_5 at a fixed potential below ground. Thus an increase in voltage across $a-b$ will increase the voltage from a to the tap 316 on the potentiometer 16 . This means the grid voltage of T_4 will be made more negative with respect to a or ground and, hence with respect to its cathode C_4 . This will reduce the current in the plate resistor R_4 of tube T_4 and, hence, decrease the negative potential on the grid G_5 of T_5 . This will result in an increase in current through the plate resistor R_5 of tube T_5 and an increase in negative potential of the grid G_6 of T_6 . Thus, the voltage drop across T_6 is increased to maintain a constant voltage across $a-b$ when the voltage from the high voltage rectifier increases. If the connection point at 17 is broken, the tubes T_4 , T_5 and T_6 maintain nearly constant voltage across a and b .

The voltage from terminal 17 being impressed on the grid G_4 of tube T_4 will vary the voltage across the output terminals a and b and thereby vary the frequency of the generator in a manner determined by its voltage versus frequency characteristic. As explained above, in a "Klystron" or similar type of oscillator the frequency increases with an increase in plate voltage and decreases with a decrease in plate voltage. For more detailed circuit connections to such an oscillator, reference is made to Figure 1 of my copending application Serial No. 446,457, filed June 10, 1942.

Since the voltage 17 is determined by the amount the generator is off frequency this voltage can be used to correct the frequency. If the drift of the generator is large it would not be possible to correct it entirely by means of the circuits shown in Figure 3 since there is usually an optimum voltage for this type of generator. However, minor corrections could be made with this circuit up to a certain point where a motor operated as illustrated in Figure 1 could take control to make a major correction in frequency. This correction would also bring the supply voltage back to normal. This combination would result in less operation of the relays and, hence, longer life for the relays.

In other words, the frequency controlling systems of Figures 1 and 3 may be used simultaneously for frequency controlling the high frequency generator HFG of Figure 1. The conductor $4F$ in this case, of Figure 3, would be connected to the terminal T of Figure 1 and the relay coil 11 of Figure 1 would be connected in shunt to the resistors 14 , 15 of Figure 3. This shunt connection is possible when the relay coil is of sufficiently high resistance, in which case it may be connected in place of resistors 14 , 15 . If the relay coil 11 is of low resistance it may be connected in series with and between resistors 14 and 15 .

The function of the condenser resistance networks $13-14$, $13-15$ of Figure 3 and the network of capacity and resistance 300 immediately above 17 is to smooth out the ripple voltage due to the pulses of current through tubes VT_1 and VT_2 . The variations of voltage at 17 due to frequency changes are of a comparatively slow rate. The function of condenser 302 between the point b and the tap 316 on the potentiometer is to in-

crease the smoothing of the power supply ripple voltage from the high voltage rectifier. This condenser will result in a higher percentage of the ripple voltage which appears across $a-b$ being impressed on the grid of T_4 than would result with just the potentiometer 16 . Of course, increased regulation of slow voltage variations across $a-b$ would result if the tap on the potentiometer could be moved to b , but this would result in excessive bias on T_4 unless glow tube regulators with an operating voltage nearly equal to the voltage across $a-b$ were used.

The resistance 318 between the grid G_4 of T_4 and the potentiometer tap is to permit the grid to follow the voltage variation on 17 . Similarly the resistance 320 between 17 and the grid of T_4 is to permit the grid to follow the voltage variations of the tap 316 . In some cases the regulation of the potentiometer would be high enough so that the resistor 318 adjacent the tap could be omitted.

The balanced detector 10 may also be used to directly operate a reversible motor for frequency control. Such an arrangement is illustrated in Figure 4. It will be noted that the armature of the reversible frequency controlling motor $4RM$ is connected between terminals $4T$ and $4T_1$. The field for the reversible motor is connected between the terminals $4T_1$ and $4T_2$.

Having thus described my invention, what I claim is:

1. In combination, an adjustable electrical device carrying high frequency oscillations, a low loss resonant element, means for exciting said element with oscillations derived from said device, a source of constant relatively low frequency waves, means for cyclically changing the tuning of said element under control of waves from said source, means for rectifying oscillations derived from said cyclically tuned element, means for rectifying waves from said low frequency source, means for combining the rectified oscillations and waves, and means responsive to the combined waves for changing the adjustment of said device.

2. In combination, a generator of high frequency oscillations having an adjustable frequency controlling device, a low loss resonant element, means for exciting said element with oscillations derived from said generator, a source of relatively low frequency waves, means for cyclically changing the tuning of said element under control of waves from said source, means for rectifying and limiting oscillations derived from said cyclically tuned element, means for rectifying waves from said low frequency source, a balanced detector for combining the rectified oscillations and waves, and means responsive to unbalance of the detector waves for changing the adjustment of said device.

3. In combination, a circuit carrying high frequency oscillations, a low loss resonant element, means for exciting said element with oscillations derived from said circuit, a source of constant, relatively low frequency waves, means for cyclically changing the tuning of said element under control of waves from said source, means for rectifying oscillations derived from said cyclically tuned element, means for rectifying waves from said low frequency source, means for combining the rectified oscillations and waves, and means responsive to the combined waves for changing the tuning of said circuit.

4. In combination, a generator of high frequency oscillations having an adjustable frequency controlling reactor, a low loss resonant element,

means for exciting said element with oscillations derived from said generator, a source of audio frequency waves, means for cyclically changing the tuning of said element under control of waves from said source, means for rectifying oscillations derived from said cyclically tuned element, means for rectifying waves from said audio frequency source, means for combining the rectified oscillations and waves, and means responsive to the combined waves for changing the adjustment of said reactor.

5. In combination, a circuit carrying high frequency oscillations, a low loss resonant element, means for exciting said element with oscillations derived from said circuit, a source of relatively low constant frequency waves, means for cyclically changing the tuning of said element under control of waves from said source, means for rectifying and limiting oscillations derived from said cyclically tuned element, means for full wave rectifying waves from said low frequency source, means for combining the rectified oscillations and waves, and means responsive to the combined waves for changing the effective frequency of operation of said circuit.

6. In combination, a circuit carrying high frequency oscillations, a low loss resonant element, means for exciting said element with oscillations derived from said element, a source of relatively low frequency waves, means for cyclically changing the tuning of said element under control of waves from said source, means for rectifying oscillations derived from said cyclically tuned element, means for combining waves derived from the rectified oscillations and waves derived from said low frequency source, and means responsive to the combined waves for changing the effective frequency of operation of said circuit.

7. In combination, a circuit carrying high frequency oscillations, a low loss resonant element, means for exciting said element with oscillations derived from said circuit, a source of relatively low frequency waves, means for cyclically changing the tuning of said element under control of waves from said source, means for rectifying and limiting oscillations derived from said cyclically tuned element, means for full wave rectifying waves from said low frequency source, means for combining the rectified oscillations and waves, and means responsive to the combined waves for changing the tuning of said circuit.

8. In combination, a circuit carrying high frequency oscillations, a low loss resonant element, means for exciting said element with oscillations derived from said circuit, a source of relatively low frequency waves, means for cyclically changing the tuning of said element under control of waves from said source, means for rectifying oscillations derived from said cyclically tuned element, means for limiting the rectified oscillations, means for rectifying waves from said low frequency source, means for combining the rectified, limited oscillations and waves, and means responsive to the combined waves for changing the effective tuning of said circuit.

9. In combination, a circuit carrying high frequency oscillations, a low loss resonant element, means for exciting said element with oscillations derived from said circuit, a source of relatively low frequency waves, means for cyclically changing the tuning of said element under control of waves from said source, means for rectifying and limiting oscillations derived from said cyclically tuned element, means for full wave rectifying waves from said low frequency source, means for

10. In combination, a circuit carrying high frequency oscillations, a low loss resonant element, means for exciting said element with oscillations derived from said circuit, a source of relatively low frequency waves, means for cyclically changing the tuning of said element under control of waves from said source, means for limiting and rectifying oscillations derived from said cyclically tuned element, means for rectifying waves from said low frequency source, means for combining the rectified oscillations and waves, and means responsive to the combined waves for changing the effective tuning of said circuit.

11. In combination, a circuit carrying high frequency oscillations, a low loss resonant element, means for exciting said element with oscillations derived from said circuit, a source of relatively low frequency waves, means for cyclically changing the tuning of said element under control of waves from said source, means for rectifying and limiting oscillations derived from said cyclically tuned element, means for rectifying waves from said low frequency source, means for combining the rectified oscillations and waves, and means responsive to the combined waves for changing the effective tuning of said circuit.

12. In combination, a circuit carrying high frequency oscillations, a low loss resonant element, means for exciting said element with oscillations derived from said circuit, a source of relatively low frequency waves, means for cyclically changing the tuning of said element under control of waves from said source, means for rectifying and limiting oscillations derived from said cyclically tuned element, means for rectifying waves from said low frequency source, means for combining the rectified oscillations and waves, and means responsive to the combined waves for changing the tuning of said circuit.

13. In combination, a generator of high frequency waves; a stable low loss concentric conductor tank circuit tuned to a desired frequency of operation, said tank circuit having its outer conductor perforated; a circuit coupling said generator to said tank circuit so as to excite said tank circuit with waves derived from said generator; a physically movable tuning device mounted for movement in said perforation so as to vary the tuning of said tank circuit; a source of 60 cycle low frequency waves; apparatus responsive to said low frequency waves for cyclically moving said device so as to vary, at a synchronous rate with respect to the frequency of said source of low frequency waves, the tuning of said stable concentric line tank about a desired frequency of operations; a detector coupled to said cyclically tuned tank circuit; a balanced vacuum tube detecting system coupled to said detector and to said source of 60 cycle waves, said detecting system producing a variable voltage as the frequency of said high frequency generator varies with respect to the mean frequency of operation of said variable tuned tank circuit, and means utilizing the variable voltage so produced for controlling the frequency of operation of said high frequency generator.

14. In combination, a generator of high frequency waves, a stable low loss concentric conductor tank circuit tuned to a desired frequency of operation, said tank circuit having its outer conductor perforated, a circuit coupling said gen-

erator to said tank circuit so as to excite said tank circuit with waves derived from said generator, an electromechanically driven tuning device mounted for physical movement in said perforated conductor so as to vary the tuning of said tank circuit, a source of low frequency waves, apparatus responsive to said low frequency waves for cyclically moving said device so as to vary the tuning of said concentric line tank about a desired frequency of operation, a detector coupled to said cyclically tuned tank circuit, a balanced detecting system coupled to said detector and to said source of low frequency waves, said balanced detecting system producing a voltage which varies as the frequency of said high frequency generator varies with respect to the mean frequency of operation of said tank circuit, and means utilizing the variable voltage produced by said balanced detecting system for controlling the frequency of operation of said high frequency generator.

15. In combination, a generator of oscillations, a stable circuit tuned to a desired frequency of oscillations generated by said generator, said stable circuit being coupled to said generator so as to be excited by oscillations generated by said generator, a source of relatively low frequency waves, means responsive to waves from said low frequency source for cyclically varying the tuning of said stable circuit about a desired frequency of operation, a rectifier rectifying waves derived from said variably tuned stable circuit, a balanced detecting system responsive to and comparing waves derived from said rectifier and from said relatively low frequency source so as to produce a voltage which varies in polarity depending upon departures in frequency of said oscillation generator away from a desired frequency of operation, and instrumentalities responsive to the voltage produced by said balanced detecting system to reduce the departure in frequency of operation of said oscillation generator away from the desired frequency of operation.

16. In combination, a generator of high frequency waves of a desired frequency, a stable low loss tank circuit tuned to said desired frequency of operation, a circuit coupling said generator to said tank circuit whereby said tank circuit is excited with waves derived from said generator, a source of low frequency waves, apparatus operated by said source of low frequency waves for cyclically and continuously changing the tuning of said tank circuit about said desired frequency of operation, a rectifier fed with waves derived from said variably tuned tank circuit, a detecting system supplied with waves derived from said rectifier and said low frequency source, said detecting system operating to combine the waves supplied to it from said rectifier and from said low frequency source to produce a voltage which changes in polarity when the frequency of said high frequency generator passes through the mean frequency of operation of said variably tuned circuit, and means responsive to said produced voltage acting to restore the frequency of operation of said high frequency generator back to a desired operating frequency.

17. In combination, a controllable system carrying high frequency oscillations, a stable tank circuit tuned to a desired frequency of oscillations generated by said generator, said stable circuit being coupled to said system so as to be excited by oscillations derived from said system, a source of relatively low frequency waves, means responsive to waves from said low frequency source for synchronously and electromechanically

varying the tuning of said stable circuit about a desired frequency of operation, a rectifier rectifying waves derived from said variably tuned stable circuit, a detecting system supplied with and responsive to waves derived from said rectifier and from said relatively low frequency source to produce a voltage which varies in polarity depending upon changes in frequency of said controllable system above and below a desired frequency of operation, and instrumentalities responsive to the voltage produced by said detecting system to change the frequency of operation of said controllable system in a direction towards the desired frequency of operation.

18. In combination, a generator of high frequency waves, a stable low loss concentric conductor tank circuit tuned to a desired frequency of operation, said tank circuit having its outer conductor perforated, a circuit coupling said generator to said tank circuit so as to excite said tank circuit with waves derived from said generator, a mechanically movable conductor mounted for movement in said perforation so as to vary the tuning of said tank circuit, a source of low frequency waves, apparatus responsive to said low frequency waves for electromechanically moving said movable conductor in the space between said concentric conductors so as to vary, in synchronism with said low frequency waves, the tuning of said stable tank circuit about a desired frequency of operation, a detector coupled to said cyclically tuned tank circuit, a balanced detecting system coupled to said detector and to said source of low frequency waves, said balanced detecting system producing a variable voltage as the frequency of said high frequency generator varies with respect to the mean frequency of operation of said stable tunable tank circuit, and means utilizing the variable voltage so produced for controlling the frequency of operation of said high frequency generator.

19. In combination, a generator of high frequency waves of a desired frequency, a stable low loss tank circuit having an outer radiation confining conductor tuned to said desired frequency of operation, a circuit coupling said generator to said tank circuit whereby said tank circuit is excited with waves derived from said generator, a source of low frequency waves, rotatable tuning apparatus mounted for movement in an opening in said outer conductor operated by said source of low frequency waves for periodically and continuously changing the tuning of said tank circuit about said desired frequency of operation, a rectifier fed with waves derived from said variably tuned tank circuit, a balanced detecting system supplied with waves derived from said rectifier and said low frequency source, said balanced detecting system operating to produce a control voltage which varies when said high frequency generator varies in frequency away from the mean frequency of operation of said variably tuned circuit, and means responsive to said produced control voltage to modify the frequency of operation of said high frequency generator.

20. In combination, a generator of high frequency waves of a desired frequency, a stable low loss two-conductor concentric line tank circuit tuned to said desired frequency of operation, a circuit coupling said generator to said tank circuit whereby said tank circuit is excited with waves derived from said generator, a source of low frequency waves, a device mounted for movement in the space between the conductors of said concentric line, apparatus operated by said source

11

of low frequency waves for synchronously and continuously moving said device thereby periodically changing the tuning of said concentric line tank circuit about said desired frequency of operation, a rectifier fed with waves derived from said variably tuned tank circuit, a balanced detecting system supplied with waves derived from said rectifier and said low frequency source, said balanced detecting system operating to produce a voltage which changes in polarity when said high frequency generator varies in frequency through the mid-frequency of operation of said variably tuned circuit, and means responsive to said voltage produced by said balanced detector to alter the frequency of operation of said high frequency generator.

21. In combination, a generator of high frequency oscillations, a stable concentric line circuit tuned to a desired frequency of oscillations generated by said generator, said stable circuit being coupled to said generator so as to be excited by

12

oscillations generated by said generator, a source of relatively low frequency waves, means responsive to waves from said low frequency source for cyclically varying the tuning of said stable circuit about a desired frequency of operation, said means including a physically movable conductor mounted for movement in an opening in said outer conductor, a rectifier rectifying waves derived from said variably tuned stable circuit, a balanced vacuum tube detecting system responsive to waves derived from said rectifier and from said relatively low frequency source to produce a voltage which varies in polarity depending upon changes in frequency of said oscillation generator above and below a desired frequency of operation, and instrumentalities responsive to the voltage produced by said balanced vacuum tube detecting system to change the frequency of operation of said oscillation generator in a direction towards the desired frequency of operation.

ORVILLE E. DOW.
